UNITED STATES PATENT OFFICE.

WILBER E. HUNTER, OF MORGANTOWN, WEST VIRGINIA.

DESIGN FOR A GOBLET OR SIMILAR ARTICLE.

50,786.

Specification for Design.

Patented May 15, 1917.

Application filed April 18, 1916. Serial No. 92,044. Term of patent 7 years.

To all whom it may concern:

Be it known that I, WILBER E. HUNTER, a citizen of the United States, and a resident of Morgantown, in the county of Monongalia and State of West Virginia, have invented a new, original, and ornamental Design for Goblets or Similar Articles, of which the following is a specification, reference being had to the accompanying drawing, forming a part thereof.

The figure is a view illustrating in elevation a goblet showing my new design.

My design may be etched, stamped,

printed, imprinted, embossed, or worked on or in or cut upon any suitable glass, china, paper, cloth or other material, or upon any metal or other suitable material, and may be produced on or in or attached to any desired article of manufacture.

I claim:

The ornamental design for a goblet or similar article as shown.

WILBER E. HUNTER.
